UNITED STATES PATENT OFFICE.

LEON N. LONGE, OF SPRINGFIELD, VERMONT.

DESIGN FOR A WATCH OR CLOCK DIAL.

40,246.

Specification for Design.

Patented Aug. 31, 1909.

Application filed March 18, 1909. Serial No. 484,332. Term of patent 7 years.

To all whom it may concern:

Be it known that I, LEON N. LONGE, a citizen of the United States, residing at Springfield, in the county of Windsor and State of Vermont, have invented a new, original, and ornamental Design for Watch and Clock Dials, of which the following is a specification, reference being had to the accompanying drawing, forming a part thereof.

The figure is a plan view of a dial, showing my new design.

I claim:

The ornamental design for a watch or clock dial as shown.

LEON N. LONGE.
